[57] CLAIM

The ornamental design for a sleeved cooler, as shown and described.

DESCRIPTION

FIG. 1 is a perspective view of a sleeved cooler showing the new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is a perspective view of an alternative embodiment of the sleeved cooler, shown in an open orientation, with all other views of this embodiment being as shown in FIGS. 2-7;

FIG. 9 is a perspective view of another alternative embodiment, with all other views of this embodiment being as shown in FIGS. 2-7, except for readily apparent dimensional differences; and,

FIG. 10 is a perspective view of a further alternative embodiment, with all other views of this embodiment being as shown in FIGS. 2-7, except for readily apparent dimensional differences.

The broken lines are for illustrative purposes only and form no part of the claimed design.
